FISHING LURE

Edgar T. Weeks, Belton, Mo.

Application June 16, 1959, Serial No. 56,379

Term of patent 3½ years

(Cl. D31—4)

Fig. 1.

Fig. 2.

Fig. 3.

Fig. 4.

Fig. 5.

Fig. 1 is a top plan view of a fishing lure, showing my new design.

Fig. 2 is a side elevational view thereof;

Fig. 3 is a bottom plan view;

Fig. 4 is an elevational view thereof taken from the left of Fig. 1; and

Fig. 5 is an elevational view thereof taken from the right of Fig. 1.

I claim:

The ornamental design for a fishing lure, as shown.
